COMBINED BARBECUE AND ROTISSERIE

Walter Koziol, Russell, Ill., assignor to Charmglow Products, Inc., Antioch, Ill., a corporation of Illinois

Filed Oct. 21, 1965, Ser. No. 87,670

Term of patent 14 years

(Cl. D81—10)

FIGURE 1 is a perspective view of a combined barbecue and rotisserie showing my design, the showing of the handle and stand is for purposes of illustration only;

What is claimed is:

The ornamental design of a combined barbecue and rotisserie, substantially as shown and described.
